SAFETY RAZOR BLADE SHARPENER

Philip H. Unsinger, Maplewood, N. J.

Application April 8, 1930. Serial No. 442,705

12 Claims. (Cl. 51—215)

This invention relates to improvements in machines employed in the manufacture of safety razor blades; and the invention has reference, more particularly, to automatic machinery for feeding blades subject to a manufacturing process step and then discharging the blades therefrom after desired treatment thereof.

In the manufacture of safety razor blades, and especially blades of the double edge type, it is desirable to avoid as much manual handling of the blades as possible, particularly in the feeding and discharging operations. This is desirable both from the standpoint of reducing labor costs, as well as from the standpoint of increasing the speed and capacity of machines. This invention, therefore, has for its principal object to provide an automatic machine having a conveyer means to receive and carry the blades successively through the machine subject to the manufacturing or processing step by which they are desired to be treated, together with a novel feed magazine for automatically delivering the blades to the conveyer means, and a novel take-off means for removing treated blades from the conveyer means and discharging the same from the machine.

This invention has for a further object to provide an automatic machine for wiping and oiling the cutting edges of razor blades preparatory to packing the same in enclosures and cartons in which the same are usually distributed.

Other objects of this invention, not at this time more particularly enumerated, will be clearly understood from the following detailed description of the same.

An illustrative embodiment of this invention is shown in the accompanying drawings, in which:—

Fig. 1 is a side elevation of a razor blade processing machine made according to the principles of this invention; Fig. 2 is a top or plan view of the same; Fig. 3 is a longitudinal vertical section of a blade feeding magazine cooperative with the conveyer means of the machine, said view being drawn on an enlarged scale; Fig. 4 is another longitudinal vertical section of said blade feeding magazine, taken on line 4—4 in Fig. 3; Fig. 5 is a top end view of said blade feeding magazine; Fig. 6 is a transverse sectional view of the same, taken on line 6—6 in Fig. 3; Fig. 7 is another transverse sectional view of the same, taken on line 7—7 in Fig. 3; and Fig. 8 is still another transverse or horizontal section, taken on line 8—8 in Fig. 3. Fig. 9 is a detail enlarged transverse section of stationary conveyer sup-

porting means or trackway devices, said section being taken on line 9—9 in Fig. 1.

Fig. 10 is a fragmentary transverse section through one set of wiping and oiling rolls, said section being taken on line 10—10 in Fig. 2, and drawn on an enlarged scale; and Fig. 11 is a similar section through the second set of wiping and oiling rolls, taken on line 11—11 in Fig. 2, and also drawn on an enlarged scale.

Fig. 12 is an enlarged fragmentary longitudinal section view showing the take-off mechanism whereby blades are removed from the conveyer means of the machine and discharged from the latter; and Fig. 13 is a horizontal section of the same, taken on line 13—13 in said Fig. 12. Fig. 14 is a fragmentary cross section taken on line 14—14 in Fig. 3.

Similar characters of reference are employed in the above-described views, to indicate corresponding parts.

Referring to said drawings, the reference character 15 indicates the bed-frame of the machine, the same being supported by suitable legs or standards 16. Journaled in suitable bearings 17 at one end of said bed-frame 15, is the carrying shaft 18 of one conveyer supporting wheel 19, and, in like manner, journaled in bearings 20 at the other end of said bed-frame 15, is the carrying shaft 21 of the other conveyer supporting wheel 22.

The conveyer means comprises an endless belt 23, preferably made of steel. This belt is of less width than the width of the blades B to be carried thereby, so that the marginal edge portions of the latter may project fully at and from each side of the belt. Fixed on said belt 23, as by riveting to project from the outer surface thereof, are longitudinally spaced studs 24 to engage through perforations in the bodies of the blades B, so as to thereby cause the latter to be propelled or carried forwardly through the machine by the conveyer belt. The peripheries of the supporting wheels 19 and 22 are preferably channeled to receive the conveyer belt, thus assuring true rectilinear movement of the courses of the belt through the machine, without lateral displacement or play.

Power transmission means are provided for actuating the conveyer belt and other devices of the machine. To this end a drive shaft 25 is journaled in bearing standards 26 located beneath the bed-frame 15. Said drive shaft 25 is driven by a drive pulley 27, which is fixed thereon, from any suitable source of power, as, for example, an electric motor (not shown). Secured to the bed-

75

85

95

110

frame 15, in depending relation thereto, is a bearing bracket 28 in which is mounted a driven shaft 29. Said shaft 29 is driven by a chain and sprocket drive 30, or other suitable driving means, from said drive shaft 25. Fixed on said driven shaft 29, so as to be rotated thereby, is a worm 31 which meshes with and drives a worm gear 32 fixed on the carrying shaft 21, thus imparting motion to the conveyer supporting wheel 22 and thereby operating the conveyer belt 23.

The blade feed magazine is located adjacent to one end of the bed-frame 15 near the conveyer supporting wheel 22. The blade feed magazine structure comprises a platform 33 mounted on a pedestal 34 connected with the bed-frame 15. Said platform 33 is provided with a channeled way 35 in its upper face, through which runs the upper, or forwardly moving, course of the conveyer belt 23, in such manner that the upper face of the latter is flush with the top or upper face of the platform 33. Overlying said platform 33 is a feed wedge plate 36, having its tapered end extending forwardly in the direction of movement of the operative or blade carrying course of the conveyer belt 23. At its under side and extending forwardly from its butt or thick end, said feed wedge plate 36 is provided with a longitudinal channel 37 adapted to provide a way or clearance for the movement of the blade engaging studs 24 which project upwardly from the upper surface of the conveyer belt. Toward the thinning or tapered end of the feed wedge plate, said channel 37 merges or communicates with a through slotted portion 38 which is aligned with and exposes the entire width of the conveyer belt to an extent slightly in excess of the width of blades B to be carried by said conveyer belt. Adjustably mounted on said feed wedge plate 36 is a wedge insert 39 of a width preferably exceeding the width of the conveyer belt but less than the width of blades to be mounted on the latter. This wedge insert is provided with a bifurcated forward end to furnish a slot 40 through which the studs 24 of the belt may project, and the arms of said bifurcated forward end are preferably laterally chamfered to reduce friction of sliding movement of blades B thereon. Said wedge insert 39 is longitudinally adjustable relative to the feed wedge plate 36 so as to dispose the same in proper position to so support the stack of blades carried in a magazine above the same, as to assure the lowermost blade of said stack being disposed in the path of movement of the conveyer studs in such manner as to be operatively engaged by a stud 24 for withdrawal from the stack and then finally operatively engaged by conveyer studs for forward propulsion under the movement of said conveyer belt, all of which will be subsequently more fully explained.

The reference character 41 indicates the base of a magazine member. Said base is adapted to register over the feed wedge plate 36 and to be secured therewith to the platform 33 by screws 42, through slotted apertures provided in said parts whereby dismounting of wedge plate and magazine structures, when desirable, is made possible. Said base 41 is provided with an opening, and secured to said base, in alignment with said opening, is an upstanding magazine member 43 open at its upper end. Said magazine member is provided in its front and rear sides with oppositely aligned slots 44, the ends of which respectively terminate short of the upper and lower ends of the magazine body. Said base 41 is cut away at its under side to provide a blade

exit passage within which is fixed a stop-block 45, suitably channeled at its underside, as at 46, to provide clearance for the conveyer studs 24, but so as to provide a stop against which the blades, immediately above the lowermost blade of the stack contained in the magazine, may abut so as to be restrained against outward movement when said lowermost blade is withdrawn. The magazine member as illustrated in the accompanying drawings, is designed to accommodate double edged perforate blades B of the kind shown. To this end the front to rear internal dimensions of the magazine member is such as to just freely receive and permit movement of the blades when the latter are disposed longitudinally between the front and rear sides of the magazine member. In order to properly support and guide the blades for downward movement through the magazine, a pair of guide rods 47 is provided to extend through the perforations adjacent the ends of the blades. Means are provided to suspend the main portions of said guide rods for downward extension through the interior of the magazine while providing upwardly projecting tapered portions 47' exteriorly disposed beyond the top end of the magazine for loading purposes. To this end each rod 47 is provided in its upper end portion with a neck 48 of reduced diameter whereby an abutment shoulder 49 is provided in connection therewith. Pivottally engaged with a supporting ear 50 connected with the upper end of the magazine member, so as to swing in horizontal plane, is coupling lever 51, having indented slots 52 entering one side thereof to receive said reduced necks 48 so as to engage the body of said coupling lever 50 beneath and in supporting and suspending relation to said guide rods. The lower free ends of the guide-rods when thus suspended, will just clear the tops of the conveyer studs 24 as the latter move beneath and past the same while the conveyer belt is in operation. In order to prevent sidewise displacement or vibration of the suspended guide-rods 47 when the magazine is loaded, detachable blade spacers 53 are provided. These spacers are of a width to snugly pass through the opposed slots 44 and are bifurcated to straddle the guide rods 47. The free ends of said spacers 53 are provided with knife-like edges 54 so as to easily pass between blades of the stack, when inserting the spacers in place. It will be obvious that said spacers 53 when applied as described will retain the blades and guide rods against lateral swaying or similar movement. The spacers will travel downwardly through the slots as the stack of blades is diminished by withdrawal of blades, and said spacers may be withdrawn and replaced at will. One or more said spacers may be employed.

In order to permit replenishing of the stack of blades within the magazine from time to time, and before the stack is completely reduced, whereby no interruption of the operation of the machine is involved in reloading the magazine, a demountable auxiliary guide-rod supporting means is provided which is adapted to adequately support and suspend the same, while the main coupling lever 51 is disengaged and swung away to permit of the threading of an additional supply of blades over the tapered portions 47' and upon the bodies of the guide rods. This auxiliary guide supporting means comprises a bifurcated coupling plate 55 having knife-like forward edges 56, the same being of a width exceeding the width of the slots 44. The margins of said slots 44 are provided with indented notches 57 to re-

80

ceive and support the coupling plate in fixed relation to the magazine body when the same is operatively attached or related thereto. The guide-
 rods 47 are provided with additional or a second
 5 set of reduced neck-^{portions} 58 to provide abut-
 ment shoulders 59. Said neck-^{portions} 58 are so
 disposed, when the guide-^{rods} are supported by
 the coupling lever 51, as to be aligned with the
 10 path of movement of the coupling plate 55 as
 defined by the notches 57 in the sides of the
 slots 44. The bifurcated end of said coupling
 plate 55 provides a slot 55' to straddle the neck-
 15 portions 58, when the coupling plate is inserted.
 In the use of the auxiliary coupling plate 55,
 20 when the upper end of the stack of blades B de-
 scends past the notches 57, the auxiliary coupling
 plate may be inserted through the slots 44 and
 notches 57 to straddle the neck portions 58 in sup-
 25 porting relation to the abutment shoulders 59,
 thereby serving to support the guide-^{rods} in op-
 erative suspended relation to and within the
 magazine interior, so that the coupling lever 51
 30 may be disengaged from the guide-^{rods} and
 swung away from across the upper open end of
 the magazine. Blades B may, when the upper
 end of the magazine is thus opened, be applied
 35 to and upon the guide-^{rods} to refill the magazine
 to the top, whereupon the coupling lever 51 may
 be returned to normal operative position and the
 auxiliary coupling plate 55 withdrawn to permit
 40 the added blades to join the top of the stack
 thereof within the magazine. It will be obvious
 that the above operations can be carried on while
 the machine continues to run and blades are be-
 ing withdrawn from the lower end of the mag-
 45 azine, and consequently no interruption of the
 machine operations with consequent loss of time
 occurs while the supply of blades within the mag-
 azine is being replenished.
 50 The operations of withdrawing the lowermost
 blade from the magazine by the conveyer means
 is as follows:—
 Owing to the downward and forward slope of
 55 the feed wedge plate 36 and its wedge insert 39,
 the lowermost blade is downwardly pitched lon-
 gitudinally so that a perforation near its for-
 ward end tipped to lie in the path of travel of the
 60 forward studs of an approaching pair of studs 24,
 while the rearward openings of the blade lie above
 the path of travel of said studs. The said for-
 ward stud, as it advances to pass under the
 65 blade, will project upwardly through the slot 40
 of the wedge insert 39, and as it reaches the for-
 ward perforation of the lowermost blade will abut
 against the forward margin thereof (as shown
 70 in Fig. 3). Having thus engaged the blade, con-
 tinued advancing movement of said stud will ex-
 75 erter an outward longitudinal sliding movement of
 said lowermost blade, the blades above being re-
 strained against accompanying movement by the
 stop-block 45 and guide-^{rods} 47. The lowermost
 80 blade will be thus carried outwardly and down-
 wardly along the slope of the wedge insert, so
 that the rearward perforation of the blade will
 descend over the rearward stud, and so that final-
 85 ly the blade will lodge flatly on the conveyer belt
 so as to be advanced thereby through the ma-
 chine. These operations will be successively re-
 peated as the stack of blades gravitates in the
 90 magazine.
 At the opposite end of the conveyer means is
 located a blade take-off or discharging means.
 This take-off or discharging means comprises a
 95 take-off plate 60 which overlies the conveyer
 belt at the point where the same advances to and
 runs over the supporting wheel 19. The inner
 100 end of said take-off plate 60 is bifurcated to pro-
 vide a suitable slot formation 61 adapted to per-
 mit the conveyer belt and its studs to extend
 through the plate, the latter being downwardly
 105 curved or sloped at its inner end to intersect the
 path of movement of the blade carrying course
 of said conveyer belt (see Fig. 12). The effective
 portions of the take-off plate 60, beyond the
 110 point where the conveyer belt passes there-
 through, is preferably of a width less than the
 width of the blades so as to leave the cutting
 edges of the blade free from contacts likely to
 115 injure the same (see Fig. 13), and is provided
 with raised longitudinal ribs 60' to reduce fric-
 tion as blades are moved thereover. Supported
 on a suitable bearing frame 62 are longitudi-
 120 nally space band wheels 63 and 64 over which
 runs a friction belt 65. Said friction belt is
 preferably made of rubber, although it may be
 made of other suitable material if desired. Said
 friction belt 65 is so disposed, as supported by
 125 the band-wheels 63—64, that its lower course
 overlies and is aligned with the take-off plate,
 and the latter is preferably upwardly bowed or
 curved to assure firm gripping contact of said
 friction-belt with blades deposited on said take-
 off plate. The band-wheels 63—64 are respec-
 130 tively provided with driving pulleys 66 and 67.
 Fixed on said shaft 18 is a pulley wheel 68. A
 drive belt 69 is arranged to run over said pulleys
 66—67 and 68 in such manner as to produce
 motion of the friction belt such as to cause its
 lower course, which is cooperative with the take-
 off plate, to move forwardly and outwardly. Lo-
 135 cated beneath and slightly outwardly off-set
 beyond the outer end of the take-off plate is a
 blade receiving means comprising a block 70
 transversely slidable between guide-members 71
 fixed on the bed-frame 15. Fixed on said block
 140 70 to stand upwardly therefrom are pairs of re-
 ceiving posts or rods 72 having tapered free ends
 73. The members of each pair of such receiving
 posts or rods 72 are spaced apart at distances
 equivalent to the distance separating the end
 145 perforation of the blades. The outer post or rod
 of each pair is preferably somewhat shorter than
 the inner post or rod. The block 70 is slidably
 reciprocable so that either pair of posts or rods
 72 may be moved into blade receiving alignment
 with the take-off plate 60, whereby while blades
 are being discharged on to one pair of posts or
 rods, blades previously delivered upon the other
 pair of posts or rods may be removed. The block
 150 70 may be fixed against displacement from an
 adjusted position by a manipulatable set screw
 74.
 It will be obvious that as the conveyer belt
 moves through and beneath the take-off plate 60,
 the blades carried by the former will ride up on
 the latter so as to be disengaged from the con-
 155 veYer studs 24 and so as to be gripped between
 the take-off plate and said friction belt 65. The
 movement of said friction belt will cause the
 blades to slide outwardly along the take-off
 plate, and finally off of the outer end of the same,
 so as to drop down upon and over the rods or
 posts 72 disposed to receive the same (see Fig.
 12).
 While advanced by the conveyer belt from the
 160 magazine to the take-off means, the blades car-
 ried by the conveyer belt may be subjected to a
 desired processing operation. In the instant
 machine means are provided for wiping and oil-
 ing the cutting edges of the blades preparatory

- to packing the same for distribution. To this end there are mounted on the bed-frame 15 two sets of wiping and oiling rolls, the first set operative to engage and treat a cutting edge at one side of a blade, and the other set operative to engage and treat a cutting edge at the other or opposite side of a blade. 80
- The first roll mechanism comprises a pair of longitudinally spaced bearing standards 75 suitably arranged for horizontal or lateral adjustment toward and away from the conveyer belt 23. Carried on each standard 75 are upper and lower bearing brackets 76 and 77 arranged for vertical adjustment. Journaled in and between the upper bearing blocks 76 is a spindle 78, provided at one end with a driving pulley 79. Suitably fixed on said spindle is an upper roll 80. In like manner, journaled in and between the lower bearing blocks 77 is a spindle 81, also provided at one end with a driving pulley 82. Suitably fixed on said spindle is a lower roll 83. The rolls 80 and 83 each preferably comprise a series of felt disks mounted side by side on the spindle and suitably fixed thereto. It has been found that Spanish white felt is admirably adapted for the purpose, since the same is readily compressible at the pinch of the rolls, and at the same time is adequately absorbent for the purpose of carrying the oil which it is desired to apply to the blade edges. By adjusting the bearing standards 75, the rolls may be nicely positioned to engage in the pinch thereof of the blade edges as the blades are moved into contact with the rolls by the conveyer means. By adjusting the bearing brackets the degree of pinch at the point of contact of one roll with the other may be determined. The rolls 80 and 83 are oppositely driven in proper direction by a belt 84, which is in turn driven from a pulley 85 fixed on the drive shaft. 100
- The courses of said belt are respectively passed over the pulleys 79 and 82, being operatively so disposed by the guidance of an idler pulley 86 (see Fig. 10). As a blade edge is passed in contact with the rolls 80 and 83, the same is engaged by the nip of the latter, and due to the compressibility of the felt of which the rolls are composed, a strong outward wiping action is exerted by the respective rolls upon opposite sides of said blade edges. This wiping action not only thoroughly cleanses the blade edges by removing all dust or other deleterious matter leaving the edge margins bright and polished, but at the same time depositing upon said edge margins a film of oil calculated to protect the edge against corrosion. 110
- In order to prevent displacement of the blades from the conveyer means, undue vibration of the blades, or other undesirable movement thereof while subject to the wiping and oiling action of the rolls, guide means to retain the conveyer belt and blades thereon in proper position while passing the rolls is provided. This guide means comprises a conveyer supporting plate 86 supported at its outer corners upon standards 37, and being, preferably, bodily supported adjacent its inner free end by an abutment post 88 upon which it rests. The lip 89 of said plate 86 underlies and supports the outer margin of the conveyer belt (see Fig. 10). Cooperative with said supporting plate 86 is guard plate 90 which is engaged by 120 dowel pins 91 carried by the outer portion of the supporting plate so as to retain the same in assembled relation to the latter. Said supporting plate is provided with a spacer boss 92 to engage the under side of said guard plate 90, to thereby limit the movement thereof toward the support- 130
- ing plate. The lip of the guard plate converges on the top of the blades carried by the conveyer belt, so as to contact with the upper surfaces of said blades inwardly of the cutting edges thereof, whereby the latter are free to pass untouched. Said lip of the guard plate is preferably formed by a lip-plate 93 secured to the underside of the free marginal portion of said guard plate. Said lip-plate 93 exceeds in length the length of the guard plate so as to provide up-turned free end portions 94 projecting beyond the ends of the guard plate (see Figs. 2, 10 and 11). These up-turned end portions 94 serve to guide the blades beneath the guard plate and its lip without obstruction, and without risk of contact at any time with the sharpened cutting edges of the blades. Said guard plate is provided with tension spring means for yieldably retaining the same in blade engaging position. 140
- The second set of wiping and oiling rolls, with cooperating guide means is located beyond the first set of rolls and guide means which has been immediately above described but so as to oppose opposite sides of the conveyer means and blades carried thereby. In detail construction and arrangement said second set of rolls and cooperating guide means is the same as the first set, as is evidenced by the application of corresponding reference characters to the parts thereof shown in the accompanying drawings. 150
- Suitable conveyer belt and blade guide track means is provided for extension between the two sets of rolls and between the respective sets of rolls and the blade feed magazine and blade take-off means. This guide track means is shown in transverse section in Fig. 9, and comprises a track-plate 95 having a channeled way 96 in its upper surface to receive the conveyer belt 23, so that the latter runs flush with the top surface of said track-plate. The width of the track-plate 95 is less than the width of the blades, so as to leave free contact therewith the cutting edges of the latter. Supported by bracket pieces 97 is a keeper track 98 which overlies the blades carried by the conveyer belt. Said keeper track 98 is provided in its under side with a channel 99 to provide clearance for the studs 24 of the conveyer belt 23. 160
- It will be evident from the above description that the instant invention provides, primarily, a novel arrangement of blade conveyer means together with an efficient feed magazine adapted to automatically deliver blades upon and in proper relation to the conveyer means. Furthermore, the invention provides a very simple and effective means for removing blades from the conveyer means and discharging the same from the machine. In addition to these features the invention provides means for thoroughly cleaning the cutting edges of blades while at the same time applying thereto a protective film of oil. 170
- As many changes could be made in the several features of construction above described and shown in the accompanying drawings, and many apparently widely different embodiments of this invention could be made without departing from the scope thereof, it is intended that all matter contained in the above description or shown in the accompanying drawings shall be interpreted as illustrative and not in a limiting sense. 180
- What is claimed is:—
1. In a razor blade processing machine, an endless conveyer having studs to engage perforations with which the blades are provided, a tubular magazine to hold a stack of blades for 190

- gravitation toward and delivery upon said conveyer, guide means engageable through perforations of the stacked blades, a main disengageable support at the upper end of said magazine to 5 suspend said guide means with its lower portion free and aligned with and above the path of movement of said conveyer studs, and an auxiliary disengageable support arranged below the upper end of said magazine to suspend said guide means when said main support is disengaged to free the upper portion of said guide means for 10 reception of blades to be added to the supply stack thereof. 2. In a razor blade processing machine, an endless conveyer having studs to engage perforations with which the blades are provided, a tubular magazine to hold a stack of blades for gravitation toward said conveyer, guide means engageable through perforations of the stacked blades, a main disengageable support at the upper 15 end of said magazine to suspend said guide means with its lower portion free and aligned with and above the path of movement of said conveyer studs, an auxiliary disengageable support arranged below the upper end of said magazine to 20 suspend when said main support is disengaged to free the upper portion of said guide means for reception of blades to be added to the supply stack thereof, a feed wedge plate at the lower 25 end of said magazine having an opening in its tapered portion for the passage of said conveyer therethrough, and an adjustable wedge insert 30 connected with said feed plate having a bifurcated tapered end portion for the upward projection of conveyer studs therethrough. 3. In a razor blade processing machine, an endless conveyor having studs to engage perforations with which the blades are provided, a tubular magazine to hold a stack of blades for 35 gravitation toward said conveyor, guide means engageable through perforations of the stacked blades, a main disengageable support at the upper end of said magazine to suspend said guide means with its lower portion free and aligned with and above the path of movement of said conveyer studs, an auxiliary disengageable support arranged below the upper end of said magazine to suspend said guide means when said main support is disengaged to free the upper 40 portion of said guide means for reception of blades to be added to the supply stack thereof, a feed wedge plate at the lower end of said magazine having an opening in its tapered portion for the passage of said conveyer therethrough, an 45 adjustable wedge insert connected with said feed plate having a bifurcated tapered end portion for the upward projection of conveyer studs therethrough, said magazine having opposed slots in its sides, and spacer plates engageable through 50 said slots and vertically movable therein, said spacer plates being insertable bodily through the stack of blades and having bifurcated end portions to straddle said guide means to retain the same and the stack of blades thereon in alignment 55 with said conveyer. 4. In a razor blade processing machine, an endless conveyer having studs to engage perforations with which the blades are provided, a tubular magazine to hold a stack of blades for 55 gravitation toward and delivery upon said conveyer, guide means engageable through perforations of the stacked blades, a main disengageable support at the upper end of said magazine to suspend said guide means with its lower portion 60 free and aligned with and above the path of movement of said conveyer studs, and an auxiliary disengageable support arranged below the upper end of said magazine to suspend said guide means when said main support is disengaged to free the upper portion of said guide means for 65 reception of blades to be added to the supply stack thereof, said magazine having opposed slots in its sides, and spacer plates engageable through said slots and vertically movable therein, said spacer plates being insertable bodily through the stack of blades and having bifurcated end portions to straddle said guide means to retain the same and the stack of blades thereon in alignment with said conveyer. 5. In a razor blade processing machine, an endless conveyer having studs to engage perforations with which the blades are provided, a tubular magazine to hold a stack of blades for gravitation toward said conveyer, guide rods engageable through perforations of the stacked blades and having tapered upper end portions to project beyond the upper end of said magazine and having their lower ends free and aligned with and above the path of movement of said conveyer studs, said rods having at points adjacent to the top of said magazine reduced necks providing abutment shoulders, and a coupling lever having indented slots to detachably embrace said necks beneath said abutment shoulder to thereby suspend said rods with their lower ends free and aligned with and above the path of movement of said conveyer studs. 6. In a razor blade processing machine, an endless conveyer having studs to engage perforations with which the blades are provided, a tubular magazine to hold a stack of blades for gravitation toward said conveyer, guide rods engageable through perforations of the stacked blades and having tapered upper end portions to project beyond the upper end of said magazine and having their lower ends free and aligned with and above the path of movement of said conveyer studs, said rods having at points adjacent to the top of said magazine reduced necks providing abutment shoulders, a coupling lever having indented slots to detachably embrace said necks beneath said abutment shoulder to thereby suspend said rods with their lower ends free and aligned with and above the path of movement of said conveyer studs, said guide rods having additional reduced necks providing abutment shoulders at points below the top of said magazine, and a detachable coupling plate having a bifurcated end portion to embrace said additional necks beneath the shoulders formed thereby, the walls of said magazine having means to receive and support said coupling plate. 7. In a razor blade processing machine, an endless conveyor having studs to engage perforations with which the blades are provided, a tubular magazine to hold a stack of blades for gravitation toward said conveyor, guide rods engageable through perforations of the stacked blades and having tapered upper end portions to project beyond the upper end of said magazine and having their lower ends free and aligned with and above the path of movement of said conveyer studs, said rods having at points adjacent to the top of said magazine reduced necks providing abutment shoulders, a coupling lever having indented slots to detachably embrace said necks beneath said abutment shoulder to thereby suspend said rods with their lower ends free and aligned with and above the path of movement of said conveyer studs, said guide rods hav-

ing additional reduced necks providing abutment shoulders at points below the top of said magazine, a detachable coupling plate having a bifurcated end portion to embrace said additional 5 necks beneath the shoulders formed thereby, the walls of said magazine having means to receive and support said coupling plate, said magazine having opposed slots in its sides, and spacer plates engageable through said slots and vertically 10 movable therein, said spacer plates being insertable bodily through the stack of blades and having bifurcated end portions to straddle said guide means to retain the same and the stack of blades thereon in alignment with said conveyer.

15 8. In a razor blade processing machine, an endless conveyer having studs to engage perforations with which the blades are provided, a tubular magazine to hold a stack of blades for gravitation toward said conveyer, guide rods engageable through perforations of the stacked 20 blades and having tapered upper end portions to project beyond the upper end of said magazine and having their lower ends free and aligned with and above the path of movement of said 25 conveyer studs, said rods having at points adjacent to the top of said magazine reduced necks providing abutment shoulders, a coupling lever having indented slots to detachably embrace said necks beneath said abutment shoulder to thereby 30 suspend said rods with their lower ends free and aligned with and above the path of movement of said conveyer studs, said magazine having opposed slots in its sides, and spacer plates engageable through said slots and vertically movable 35 therein, said spacer plates being insertable bodily through the stack of blades and having bifurcated end portions to straddle said guide means to retain the same and the stack of blades thereon in alignment with said conveyer.

40 9. In a razor blade processing machine, an endless conveyer having studs to engage perforations with which the blades are provided, means adjacent to an end of said conveyer for removing blades therefrom, comprising a take-off 45 plate angularly intersecting the path of movement of said conveyer and having a bifurcated inner end to straddle and pass the latter, and a frictional drive belt having its lower course contiguous to and longitudinally slidable along the 50 top of said take-off plate, to grip blades deposited on said take-off plate for sliding said blades along

said plate and discharging the same therefrom.

10. In a razor blade processing machine, an endless conveyer having studs to engage perforations with which the blades are provided, means adjacent to an end of said conveyer for 80 removing blades therefrom, comprising a take-off plate angularly intersecting the path of movement of said conveyer and having a bifurcated inner end to straddle and pass the latter, and a frictional drive belt having its lower course contiguous to and longitudinally slidable along the top of said take-off plate, to grip blades deposited on said take-off plate for sliding said blades along 85 said plate and discharging the same therefrom, and a blade stacking means having upstanding rods adjacent to the outer end of said take-off plate and over which perforations of the discharged blades register, whereby the latter fall onto said rods when free from the grip of said drive belt.

11. In a razor blade processing machine, an endless conveyer having studs to engage perforations with which the blades are provided, means adjacent to an end of said conveyer for removing blades therefrom, comprising a take-off plate 100 angularly intersecting the path of movement of said conveyer and having a bifurcated inner end to straddle and pass the latter, and a frictional drive belt having its lower course contiguous to and longitudinally slidable along the top of said take-off plate, to grip blades deposited on said take-off plate for sliding said blades along said plate and discharging the same therefrom, and a blade stacking means comprising, a shiftable block below and adjacent to the outer end of 105 said take-off plate, said block having a plurality of pairs of upstanding rods selectively movable into line with said take-off plate and over which perforations of the discharged blades register, whereby the latter fall onto said rods when free from the grip of said drive belt, said pairs of rods being selectively disposed in blade receiving 110 position by moving said block.

12. In a razor blade processing machine as set forth in claim 9, in which the take-off plate is 120 provided with laterally spaced longitudinal ribs on its upper surface to reduce frictional contact of blades moved thereover by said friction drive belt.
